PLAQUE UNIT FOR WALL COVERING OR SIMILAR ARTICLE

Nathaniel Hyman, Woodmere, N. Y.

Application October 15, 1949, Serial No. 5,508

Term of patent 14 years

(Cl. D59—10)

To all whom it may concern:

Be it known that I, Nathaniel Hyman, a citizen of the United States, residing at Woodmere, in the county of Nassau and State of New York, have invented a new, original, and ornamental Design for a Plaque Unit for Wall Covering or Similar Article, of which the following is a specification, reference being had to the accompanying drawing, forming part thereof.

In the drawing:

Fig. 1 is a front elevational view of a plaque unit for wall covering or similar article, showing my new design;

Fig. 2 is a sectional view as taken along the lines 2—2 of Fig. 1.

Fig. 3 is a rear elevational view thereof.

I claim:

The ornamental design for a plaque unit for wall covering or similar article, as shown.

NATHANIEL HYMAN.
